UNITED STATES PATENT OFFICE

FORREST FREDRICK BEIL, OF CLINTON, IOWA, ASSIGNOR TO CURTIS COMPANIES,
INCORPORATED, OF CLINTON, IOWA

WINDOW FRAME CONSTRUCTION

Application filed April 14, 1930. Serial No. 444,200.

The object of my invention is to provide an improved type of window frame construction of simple, durable and comparatively inexpensive structure.

5 Still a further object is to provide a window frame adapted for various types of building constructions and constructed so that a more weatherproof frame and window is provided. Another object is to provide such a frame 10 which more effectively prevents air infiltration and one which sacrifices none of the advantages of the window frames now being generally manufactured.

Still a further object is to provide a flat portion 15 on the under surface of the sloping sill, which may be provided by a level bottom groove, such flat portion being adapted for resting on top of a flat lower side of a window opening, so as to align the window frame 20 relative to the building in which it is set.

Another object is to provide a window frame having side and head jambs, each 25 formed of a main jamb member and a strip, which I shall term a conversion strip, such strip being adaptable for either edgewise or sidewise attachment to the edge of the jamb member for converting the window frame to different types of building constructions.

Still a further object is to provide notches 30 in the sill for the conversion strips on the side jambs to extend into, the portions of the conversion strips extending into the notches being nailed to the sill for supporting it relative to the window frame adjacent the inner 35 edge of the sill.

Still a further object is to provide an improved attaching means for the outer side of the sill relative to the side jambs of the window frame, such attachment means being provided by a screw extending from an angular socket in the side jamb into the sill.

Still a further object is to provide a weatherseal strip adapted to coact with the side jamb when brick veneer constructions are 45 used.

With these and other objects in view, my invention consists in the construction, arrangement and combination of the various 50 parts of my window frame construction whereby the objects contemplated are at-

tained, as hereinafter more fully set forth, pointed out in my claims, and illustrated in the accompanying drawings, in which:

Figure 1 is a vertical, sectional view through a window frame embodying the features of my invention. 55

Figure 2 is a horizontal, sectional view of the same, showing one side of the window frame and illustrating the use of sheathing and siding on the building in which the frame 60 is mounted.

Figure 3 is a similar, sectional view illustrating brick veneer applied to a frame building.

Figure 4 is a similar sectional view illustrating brick veneer applied to solid masonry walls. 65

Figure 5 is an enlarged, sectional view similar to the lower portion of Figure 1, illustrating how a level spot on the under 70 surface of the sloping sill coacts with the bottom of a window opening of a shape modified from the showing of Figure 1.

Figure 6 is a perspective view of one end 75 of the sill, the lower end of a side jamb and the lower end of one of the conversion strips, the parts being separated; and

Figure 7 is a sectional view on the line 7—7 of Figure 6 illustrating the screw for attaching the side jamb to the sill. 80

On the accompanying drawings, I have used the reference numeral 10 to indicate the sill of a window frame A. The side jambs of the frame A are indicated at 12 and the head jamb thereof at 14. 85

The upper and lower sashes of the window frame A are indicated by the reference characters B and C respectively. The frame A also includes the usual inner and outer casing members around the window frame, but these 90 are not numbered on the drawings.

The sill 10 is preferably of considerable slope to facilitate the drainage of water on the sill toward the outside of the building. In the bottom of the sill 10, a water drip groove 95 16 is provided, and a pair of grooves 18 and 20 are provided for the tongue of sheathing 22 and the upper edge of siding 24 respectively, as best illustrated in Figure 1. With a groove for both the sheathing and the sid- 100

ing a much more effective weatherproof joint is provided at the bottom of the window frame A.

As indicated at 26 and 28, a level bottom 5 groove is provided so that when the window frame A is applied to sheathing that does not have a tongue, as indicated at 22a, in Figure 5, the portions 26 and 28 may rest on the flat 10 upper surface of the sheathing 22a for aligning the window frame A relative to the window opening.

It will be obvious that with nothing but a sloping lower surface to rest on the sheathing 22a, any slight misalignment outward or inward 15 of one end of the sill would cause the window frame to assume a non-vertical position, which is objectionable.

Instead of providing side and head jambs extending completely from the outer casings 20 to the inner casings of the window frame, I make the jambs somewhat narrower and widen them to the proper width by conversion strips 30.

The edges of the strips 30 are grooved as 25 indicated at 32 and the sides thereof are grooved as indicated at 34. The rear edge of the jambs 12 and 14 are tongued as indicated at 36.

In ordinary frame building construction 30 where siding is used outside of the sheathing, the conversion strips 30 are mounted flatwise as illustrated in Figures 1 and 2 of the drawings, with the tongues 36 coacting with the grooves 34.

35 The side jamb conversion strips instead of stopping on top of the sill 10 as the side jambs themselves do, extend on down past the sill, being located in notches 38 cut in the inner ends of the sill. The portions of conversion strips which extend into the notches 38 are nailed to the sill as indicated by the dotted showing of the nail 40 in Figure 2.

The rear edge of the sill is held in supported position relative to the window frame 45 A by the nails 40. The outer edge of the sill is supported by screws 42 which extend through openings 44 arranged at an angle from a socket 46 in each side jamb 12 to the lower end of the side jamb.

50 The screws 42 extend into the sill 10 as best shown in Figure 7 of the drawings. The lower ends of the side jambs 12 preferably extend into dadoes 48 formed in the ends of the sill 10, so as to properly align the side 55 jambs relative to the sill.

Where it is desirable to use the window frame in brick veneer construction of a frame building, as shown in Figure 3, an air space indicated at 50 is usually left between the sheathing 52 and the veneer bricks 54.

60 I have provided a weatherseal 56, consisting of a vertically arranged board to overlap the bricks 54, and having a tongue 58 to extend into a groove 60 formed in the outside 65 of the side jamb 12. The extra thickness

taken up by the weatherseal 56 increases the thickness of the wall, and the conversion strips 30 are therefore applied to the jambs edgewise, as shown in Figure 3, with nails 40a, extending into the sill. Thus the same conversion strip may be used for either type of construction as illustrated in Figures 2 and 3, by merely changing it from one position to another. In either position, the conversion strip serves the purpose of supporting 75 the inner side of the sill.

In Figure 4, I have illustrated the weather-seal 56 and the conversion strip 30 applied edgewise in a solid masonry construction with 80 brick veneer.

A window frame constructed in accordance with the above description is readily adaptable to various types of building constructions with a minimum amount of labor in installing the frame. The particular way of securing the sill to the side jambs and conversion strips eliminates all loosening of the sill joint. The frame can also be applied to the newer walls formed of plaster board or other thin wall material by omitting the conversion strip or slightly altering it.

The window to which my construction is applied may be of the weightless type illustrated in Figures 2 and 3 of the drawings or 95 may be of the type having weight boxes as illustrated in Figure 4. In this figure members 62 and 64 cooperate with the side jamb 12, the conversion strip 20 and the weather seal 56 to form a weight box. The member 64 may be provided with a tongue 66 if desired 100 to fit into the groove of the conversion strip.

Screens and storm sash may be accommodated in the ordinary way, the sill 10 having a shoulder 62, for them to abut against.

The frame A and the window sashes B and C are easily installed the same as in present day constructions.

Some changes may be made in the construction and arrangement of the parts of my window frame construction, without departing from the real spirit and purpose of my invention, and it is my intention to cover by my claims, any modified forms of structure or use of equivalents, which may be reasonably included within their scope.

I claim as my invention:-

1. In a window frame, a jamb having a tongue along its inner edge, a strip of greater width than thickness and having two grooves, one in its face and the other in its edge, said strip being adapted to be applied either flat-wise or edge-wise to said jamb with one of said grooves engaging said tongue.

2. In a window frame, a jamb having a tongue along its inner edge, a strip of greater width than thickness and having two grooves, one in its face and the other in its edge, said strip being adapted to be applied either flat-wise or edge-wise to said jamb with one of said grooves engaging said tongue, said

grooves being equi-distant from an edge and a face respectively of said strip whereby when said strip is applied in either position it will be flush with the inner face of the jamb.

5. 3. In a window frame, a sill, a side jamb, a strip applicable to said side jamb either flat-wise or edge-wise and flush with the inner face of the same when in either position for widening the jamb to a greater or less extent respectively as required, said strip having one side thereof in alignment with the inner face of said side jamb whereby said strip, when applied to the jamb edge-wise or flat-wise, will abut said face.
- 10 4. In a window frame, a sill, a side jamb, a strip applicable to the inner edge of said side jamb either edge-wise or flat-wise thereagainst for widening said jamb to a greater or less extent respectively, said sill having a notch with one face of which said strip engages when said strip is in either of said positions.

5. In a window frame, a sill, a side jamb, a strip applicable to an edge of said side jamb either edge-wise or flat-wise thereagainst for widening said jamb to a greater or less extent respectively, said sill having a notch provided with two faces, one in alignment with said edge of said side jamb, said strip engaging

30 said face when in either of said positions.

6. In a window construction, a sill, a side jamb and means for securing the two together, comprising a screw extending through the side jamb and into the sill and positioned adjacent the outer edge of the jamb and a separable extension member attached along the inner edge of the jamb and extending past and secured to the sill adjacent the inner edge thereof said separable extension member being adapted for varying the width of said jamb to suit different wall thicknesses.

7. In a window construction, a sill, a side jamb and means for securing the two together comprising a screw extending through the side jamb and into the sill and positioned adjacent the outer edge of the jamb and a separable extension member attached along the inner edge of the jamb for varying the width to suit different wall thicknesses and extending past and secured to the sill adjacent the inner edge thereof, said sill having a notch to engage two faces of said extension member.

8. In a window frame, a sill, a jamb terminating in the upper face of said sill, a separate strip along the inner edge of said jamb and secured thereto for varying the width thereof and a vertical notch in the inner edge of said sill, said strip being longer than said jamb and extending past and engaging in the notch in said sill for attachment to the sill when the parts of said window frame are in assembled relationship.

9. In a window frame, a sill, a side jamb above said sill, a separate strip along the inside edge of said jamb for varying the width

thereof and secured thereto and a vertical open notch in the inner edge of said sill, said separate strip being aligned vertically with said notch and engaging with two of its faces in the notch in the sill when the window is assembled.

Des Moines, Iowa, March 17, 1930.
